UNITED STATES PATENT OFFICE.

LIONEL FLEISCHMANN, OF BERLIN-WILMERSDORF, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

LOUD SPEAKER.

Application filed November 13, 1926, Serial No. 143,183, and in Germany January 22, 1926

The present invention relates to loud speakers, or speaker units in general, and has for its principal object the method and means of developing a unit in which the variations 5 in current caused by different sound intensities will be carried to a point discharge rather than to a diaphragm. By this means of reproduction of sound more faithful operation is insured.

10 In loud speaker units of the present commercial type the difficulty appears to rest in the fact that the diaphragms which are used to produce the vibrations in the air possess a certain mass and a natural elasticity. This 15 results in imperfect proportional reproduction of the electrical excitation because of the natural frequency of each separate diaphragm.

It has been known for a long period of time 20 that electro-static point discharges possess the property of imparting a motional impulse to the air, which motional impulses depend upon the potential at the point as soon as the critical potential is surpassed. For most 25 gases the critical potential ranges from 2000 to 3000 volts.

From the above description it is seen that 30 it is necessary that a point be supplied with a constant direct current potential bias which should not exceed a certain minimum where 35 a discharge is produced, upon which the variable potential of the tone-frequency (audio-frequency) wave is superimposed so as to cause the point to discharge. However, it is 40 also possible to obtain vibrations of the air with the direct current potential bias if the 45 point or points are supplied with alternating current of corresponding potential.

The presence of the direct current potential 50 has been found, however, to easily lead 40 to arc discharges which are accompanied by disagreeable noises. Another object of this invention, therefore, is to eliminate such a 55 tendency to arc discharge by introducing a dielectric material possessing an infinitely high or very high resistance between the two 60 electrodes. This dielectric material will serve to prevent arcing between the electrodes.

55 One form of electrode which I propose to use comprises two metal disks, one of which is studded with a relatively large number of sharp needles. To insure the highest possible 65 sound volume, the needles must have

definite lengths and must be spaced at definite 55 distances from one another. It is suitable to embed the needles partly in insulating material which can be accomplished by passing the electrically connected needles through a disk of insulating material, instead of using 60 the metal disk to carry the needles.

The preferred form of my invention is illustrated by the single figure in the accompanying drawing.

Referring to the drawing, the energy 65 transmitted is received on the antenna A from which it is carried to the receiver of any preferred form. The audio frequency output is then carried by means of conductors 5—5 to plates 1 and 3. The plates 1 and 3 70 are of metal and spaced at any preferred distance with respect to each other. The plate 1 is provided with a plurality of points 2 which are carefully constructed and mounted in the plate 1 so as to be spaced at equal distances *a* from each other and extend equal distances *b* above the surface of the plate 1 75 to insure the highest possible sound volume. The plate 1 is preferably circular and has the points 2 distributed about its surface with 80 equal spacing between each of the said points.

Surrounding the plate 1 and separating the discharge points 2 from each other is a disk, casing or covering of a dielectric material 4 to prevent arcing between the electrodes. The battery or other suitable energy 85 source 6 is connected with the plates 1 and 3 through the leads 7 and 8 respectively, and is for the purpose of obtaining the proper potential in the points at all times.

90 While I have described only a single detail of my invention, the same is capable of being adapted to other modified forms such as may occur to those skilled in the art and I am entitled to all modifications thereof that 95 fall fairly within the spirit and scope of my invention as defined by the appended claims, wherein:

I claim:—

1. The method of reproducing sound which 100 comprises superimposing a variable potential of audio frequency upon a definite potential bias at a point, obtaining thereby an electrostatic point discharge into the atmosphere and creating by said electrostatic point discharge 105 trains of sound waves varying in proportion to the varying audio potential.

2. The method of reproducing sound which

comprises, receiving radio signals and converting the same into varying audio pulses, conveying the varying audio pulses to a point, biasing the point by a definite potential near the critical discharge value and producing an electrostatic point discharge by the superimposing of said varying audio pulses upon said biased discharge point, thereby producing trains of sound waves in the atmosphere proportional to the audio pulses.

3. An arrangement for reproducing sounds comprising, a plurality of disk electrodes, a plurality of equally spaced points mounted in one of said electrodes, means for producing a steady bias potential near the critical discharge value on said points, and means for superimposing varying audio pulses on said bias potential whereby said electrode provided with said spaced points will be discharged 20 energy to the other of said electrodes and produce in the atmosphere between said electrodes a train of sound waves proportional to said audio pulse.

4. An arrangement for reproducing sounds comprising, means for receiving radio signals and converting the same into varying audio pulses, a plurality of spaced electrodes, means for producing a steady potential bias on said electrodes, said bias potential being near the critical discharge point for said electrode spacing, and means for superimposing said audio pulses on said biased electrodes whereby electrostatic point discharge occurs between said electrodes and trains of sound waves are produced in the atmosphere between said electrodes varying in proportion to said audio pulses.

5. An arrangement for reproducing sounds comprising, means for receiving radio signals and converting the same into varying audio pulses, a plurality of spaced disk electrodes and a layer of atmosphere therebetween, a dielectric material surrounding one of said electrodes, a biasing means for applying a potential approaching a discharge potential on said electrodes, means for superimposing said

varying audio potential on said biased electrodes, whereby an electrostatic discharge occurs between said electrodes and a sound wave is produced in the atmosphere separating 50 said electrodes.

6. An arrangement for reproducing sounds comprising, a plurality of disk electrodes separated by a layer of atmosphere, an insulating material surrounding one of said electrodes, a plurality of spaced discharge points mounted in said last named disk and extending through said insulating material, means for impressing a steady bias potential near the critical discharge value upon said points, means for 60 receiving radio frequency signals and converting the same into varying audio frequency pulses, and means for superimposing said varying audio pulses upon said potentially biased electrodes for producing point discharge between said electrodes, whereby sound waves are circulated in the atmosphere between said electrodes which correspond to the received signals.

7. An inertialess speaker system comprising 70 a corona discharge device, and a source of sound varied electrical energy coupled to said device to modulate the intensity of the corona.

8. An inertialess speaker system comprising 75 a corona discharge device, an electrical circuit including a source of unmodulated electrical energy for energizing said device, and a source of sound varied electrical energy coupled to said circuit to modulate the intensity of the corona.

9. In combination, an inertialess speaker comprising a corona discharge device located in the air medium which is to carry the sound, a source of electrical energy for energizing said device at a constant value, and a source of 85 modulated electrical energy arranged to modulate the resultant corona.

10. In combination, an inertialess speaker comprising a corona discharge device, and means including a radio receiver to energize 90 said device.

LIONEL FLEISCHMANN.
